CAN OPENER CUTTER ASSEMBLY

William J. Landry, Blue Springs, Mo., assignor to
John C. Hockery, Kansas City, Mo., trustee for
Henry J. Talge and Foster L. Talge

Application November 21, 1951, Serial No. 257,466

7 Claims. (Cl. 30—9)

This invention relates to can openers and more particularly to can opener cutter assemblies.

This application is a continuation-in-part of Serial No. 129,139, filed November 23, 1949, now Patent No. 2,602,991, and Serial No. 204,533, filed January 5, 1951, now Patent No. 2,619,718.

An object of this invention is to provide a can opener cutter assembly having a cutter which is easily removable by the housewife for cleaning, sharpening and replacement.

A further object of this invention is to provide a can opener with a cutter locking arrangement which will lock only when the cutter is properly positioned on its support.

Other and further objects of this invention will appear from the following description.

In the following drawings, which form a part of the instant specification, and are to be read in conjunction therewith, there is shown embodiments of the invention and in the various views, like reference numerals are used to indicate like parts.

Fig. 1 is a plan view of a can opener embodying the invention with a can top removing magnet attached.

Fig. 2 is a side view of the can opener in Fig. 1. Fig. 3 is an end view of the can opener in Fig. 1 with parts in section.

Fig. 4 is a fragmentary side view with the magnet removed to show the cutter mounting arrangement.

Fig. 5 is a perspective view taken from below.

Fig. 6 is a view of the locking clip taken along the line 6—6 in Fig. 3 in the direction of the arrows.

The invention as hereinafter described comprises a can opener cutter assembly which is mounted upon a can opener 10 operated by a handle 11. Mounted on the same shaft 12 as the handle is a feed wheel 13. By operation of the handle 11 the can opener cutter assembly is moved toward and away from the feed wheel 13 in the can cutting operation. On an inset portion 14 of the housing of the opener is a screw 15 to which may be attached an L-shaped bracket 16 supporting a can top removing magnet 17. The L-shaped bracket 16 has one arm 16a bifurcated to engage screw 15 and one arm 16b apertured to receive a screw attachment 18 on the magnet 17. Arm 16a is adjustable on screw 15 to position the magnet at a greater or lesser distance from the opener.

Above the feed wheel 13 there is a recessed opening 19 in the housing wherein is located the cutter assembly. This assembly has a base 20

20 supported by a shaft 21 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

The cutter assembly is supported by a cutter post 24 which is supported by a housing 22. The cutter assembly has a cutter 23 which is supported by a cutter post 24.

blade to the outside, there is no hindrance to the free movement of the locking clip.

From the foregoing description it will be seen that there has been provided a can opener cutter assembly with a cutter that may easily be removed by the housewife for cleaning, sharpening, or replacing. There also has been provided a locking arrangement holding the cutter in position and operating so as to prevent mistakenly replacing the cutter in the reverse position. There has also been provided a unique type of bracket for the magnet.

From the foregoing it will be seen that this invention is one well adapted to attain all of the ends and objects hereinabove set forth together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

Having thus described my invention, I claim:

1. A can opener cutter assembly carried by the housing of a can opener including a cutter with a bearing disk rotatably and removably mounted on a post, a groove around the post engaged by a pivoted locking clip, said clip having a projection engageable by the cutter bearing disk when the cutter is improperly mounted on the cutter post thereby preventing latching of the clip on the cutter post.

2. A can opener cutter assembly as in claim 1 in which the cutter has an annular hub on the side of the blade opposite the bearing disk.

3. A can opener cutter assembly comprising a base with two posts mounted thereon, a cutter with a bearing disk rotatably and removably mounted on one of said posts, a groove around the cutter mounting post engaged by a locking clip pivotally attached to the post other than the cutter mounting post, said clip having a projection engageable by the cutter bearing disk when the cutter is improperly mounted on the cutter post, thereby preventing latching of the clip on the cutter post.

4. In a can opener, a body having a spindle projecting outwardly therefrom, a cutter wheel rotatably mounted on said spindle with its inner face adjacent the body, said wheel having a central hub of reduced diameter projecting from the outer face thereof, a latching finger normally having one end adjacent the outer end of said hub and covering a portion thereof to retain the wheel on said spindle, said finger having a portion spaced axially inward from the end of the hub and disposed adjacent said outer face of the wheel, said finger being pivotally

mounted on said body to swing about an axis spaced laterally from said spindle, whereby said one end of said finger is movable away from the spindle to a position where said finger is clear of the wheel thus to permit removal of the wheel from the spindle.

5. In a can opener, a body having a spindle projecting outwardly therefrom, a cutter wheel rotatably mounted on said spindle with its inner face adjacent said body, said spindle containing a surface groove adjacent and parallel to the outer face of said wheel, a latching finger normally having one end adjacent the outer face of said wheel and covering a portion thereof to retain same on said spindle, said finger in its normal position having a portion thereof received in said groove to prevent shifting of said one end axially of the spindle, said finger being pivotally mounted on said body to swing about an axis spaced laterally from said spindle whereby said one end thereof is movable out of said groove and away from the spindle to a position where said finger is clear of the wheel thus to permit removal of the wheel from the spindle, said wheel and finger having interfering shoulder portions which prevent said finger from being returned to said normal position if the wheel is remounted on said spindle with its two faces reversed in position.

6. In a can opener of the type having a cutter wheel and a cooperating feed wheel for engaging the flange of the can to advance same relative to said cutter wheel, a body having said feed wheel rotatably mounted thereon, a spindle projecting outwardly from said body at an oblique angle to the axis of rotation of the feed wheel, said cutter wheel being rotatably mounted on said spindle, a post projecting outwardly from said body at a point disposed rearwardly of the point of action of said wheels, said post adapted to engage the rim of a can to prevent tilting of same, a latching finger pivotally mounted on the outer end of said post, the free end of said finger being movable between a first position adjacent the outer face of the cutter wheel wherein the finger covers a portion of the wheel to retain same on the spindle and a second position clear of the wheel, whereby the cutter wheel may be withdrawn from the spindle when the finger is in the latter position.

7. A can opener as in claim 6 wherein said post is substantially parallel to said spindle.

WILLIAM J. LANDRY.
